ELECTRODE LEAD-IN FOR METAL VACUUM
VESSELSWalter Dällenbach, Berlin-Charlottenburg, Ger-
manyApplication October 25, 1934, Serial No. 749,984
In Germany October 30, 1933

7 Claims. (Cl. 250—27.5)

My invention relates to electrode lead-ins for metal vacuum vessels and particularly for metal tanks used for vacuum discharge apparatus, such as mercury vapor rectifiers.

5 It is an object of my invention to provide a reliable lead-in for the electrodes in a tank of the type referred to.

To this end, I provide a metal member, such as a plug, in which an electrode is inserted, and a 10 member, for instance, a sleeve of refractory material, which receives the plug with the electrode and is inserted in the tank, so that, when the sleeve is sintered at high temperature, a vacuum-tight connection is effected between said sleeve 15 and said plug, on the one hand, and between said sleeve and the tank, on the other hand.

It is very difficult to obtain a reliable electrode lead-in for vacuum discharge apparatus with metal tanks, particularly if such tanks are subjected to treatment at 300 to 400 degrees for 20 permanently separating them from the vacuum pump.

Various solutions of the problem have already 25 been proposed and are substantially satisfactory with regard to reliability. However, the existing lead-ins require extra supporting means for the electrodes whose weight is considerable, particularly for heavy currents. The vacuum-tight sealing means themselves cannot support the electrodes, and it is obvious that the initial cost of the lead-in is much increased by the extra supporting 30 means.

It has also been proposed to provide an insulating member of refractory material which is 35 connected to the vacuum tank and directly supports the weight of the corresponding electrode. However, it has not been possible heretofore to effect a connection between the insulating member and the electrode, and the wall of the tank, 40 which is permanently vacuum-tight and, at the same time, able to support the weight of the electrode, so that connections including an insulating member of the kind referred to, had to be abandoned notwithstanding their simplicity and 45 cheapness.

I have found that the failure of the said lead-ins is due to the use of unsuitable materials and unsuitable connecting means.

According to my invention, a reliable and 50 highly vacuum-tight lead-in is obtained by utilizing the sintering of the insulating member for making the connection between the electrode and the member on the one hand, and the member and the wall of the tank, on the other hand, or 55 by obtaining the connection through the medium

of a glass or enamel melt whose heat-expansion coefficient is substantially equal to that of the material of the insulating member. The areas of the faces by which the parts are connected, are made so large that the mechanical stresses from 5 the weight of the electrodes are taken up without extra supporting means for the electrodes.

Thorough investigation has demonstrated that in the manner described an electrode lead-in is 10 obtained in which the weight of the electrodes is supported without extra means, and the lead-in 15 does not become leaky and is not damaged by the weight.

Preferably, the metal parts to be connected to the insulating member are made of a material 15 whose heat-expansion coefficient is substantially equal to that of the insulating member, and the melt. However, the heat-expansion coefficient of the metal parts may be somewhat higher than that of the insulating member and the melt, as 20 this brings about shrinking which is favorable for the tightness and strength of the connection.

As the connection by sintering of the insulating member, or by glass or enamel melt, is made at 25 very high temperatures, the electrode lead-in is absolutely resistant to the aforesaid heating to 300 to 400 degrees for removing the gas from the tank.

In the accompanying drawing, three types of 30 lead-ins embodying my invention are illustrated by way of example.

In the drawing—

Fig. 1 is a section of a lead-in whose insulating member is sealed against leakage by sintering of the member onto the metal parts, and

Fig. 2 is a section of a lead-in which is sealed 35 by a melt.

Referring now to the drawing, and first to Fig. 1, the wall of a vacuum tank is indicated at 7, and the conductor 4 of an electrode 5 is led in through an insulating member or sleeve 1. The sleeve is made of refractory material, preferably steatite, which, as is known, is a refractory product obtained by burning silicate of magnesia, the initial product being normally talc. Steatite is superior to porcelain not only on account of its greater mechanical strength but also because it has a higher coefficient of heat expansion which is equal to glass or iron.

A plug 2 of metal is inserted at the upper 50 end of sleeve 1 and an annulus 3, also of metal, is placed about the sleeve at its lower end. The plug 2 and the annulus 3 are made of a metal, or alloy, whose heat-expansion coefficient is substantially equal to that of the refractory ma- 55

aterial of the sleeve 1, in the present instance, steatite. The heat-expansion coefficient of pure iron is 11 to 12 millionths per degree, and may be reduced to less than 10 millionths per degree by alloying with nickel, chromium, or vanadium. Two or more of the said metals may be added to iron for reducing its heat-expansion coefficient, and alloys of chromium and nickel may be used instead of iron alloys. Whatever may be the constituents of the alloy, they should be so selected as to make the heat-expansion coefficient of the metal parts substantially equal to that of the sleeve 1.

The plug 2, and the annulus 3, are embedded in the sleeve 1 while the sleeve is in unburnt condition, and a vacuum-tight connection is thus obtained. Upon burning, the steatite and the metal parts are permanently and vacuum-tightly connected by sintering. After the unit including the sleeve 1, the plug 2, and the annulus 3, has been burnt in a suitable furnace, it is removed and the conductor 4 of the electrode 5 is inserted in a central hole of the plug, and welded. Preferably, an annular welding groove is formed in the boss of the plug at 6. A wire may be connected to the conductor 4 by a bore 8 in its outer end. Finally, the annulus 3 is inserted in a hole of the wall 7, and welded to the wall.

The unit 1, 2, 3 is built up as a self-contained part because, as described, it is burned in a furnace while the welding operations at 2 and 3 can be performed anywhere, and because its metal parts 2 and 3 are comparatively small and cheap in proportion, as against a tank made of chromium-nickel or other alloy, whose cost would be prohibitive.

Referring now to Fig. 2, the arrangement of parts is the same as described with reference to Fig. 1 but here the plug 2 is connected to the sleeve 1 by a melt 9 of glass or enamel, and the annulus is connected to the sleeve by a melt 9'. The operation is performed without difficulty, as the melting point of the glass or enamel is normally below the point at which the steatite of the sleeve becomes plastic. The heat-expansion coefficient of the melt should be substantially equal to that of the metal or alloy of the plug 2 and annulus 3, and of the material of sleeve 1.

The term "cylindroid" as used in the claims is intended to indicate a surface which is either that of a cylinder in its broadest sense or of a similar polyhedron such as a conical or prismatic frustum. The term "cylinder" in this definition is used in its broadest sense as including any surface formed by the movement of a line around another line to which the first line is parallel, and therefore includes elements of any cross section.

I claim:

1. A short, shallow seal for a lead-in construction for vacuum discharge apparatus, comprising a metal member adapted to form a part of the wall of a vacuum vessel, a metal electrode lead-in adapted to support an electrode, an insulating member fitting in said metal member for supporting directly said lead-in, said insulating member comprising a sleeve of steatite, said lead-in passing through said sleeve, a metal plug secured to said lead-in and secured to said sleeve, the areas of contact between said sleeve and said metal member and plug having substantially cylindroidal form, said metal member and plug being formed of material having

substantially the same coefficient of expansion as steatite, and sealing joints at said areas of contact forming a vacuum tight seal between said sleeve and said metal member and plug, the axial lengths of said sealing joints being relatively short compared to the diameters thereof.

2. In a device as claimed in claim 1, said metal member and plug being composed of an alloy selected from the group consisting of nickel-iron, chromium-iron, vanadium-iron, and chromium-nickel alloys.

3. A short, shallow seal for a lead-in construction for vacuum discharge apparatus, comprising a metal member adapted to form a part of the wall of a vacuum vessel, a metal electrode lead-in adapted to support an electrode, an insulating member fitting in said metal member for supporting directly said lead-in, said insulating member comprising a sleeve of steatite, said lead-in passing through said sleeve, a metal plug secured to said lead-in and secured to said sleeve, the areas of contact between said sleeve and said metal member and plug having substantially cylindroidal form, said metal member and plug being formed of material having substantially the same coefficient of expansion as steatite, and sealing joints of fused material at said areas of contact forming a vacuum tight seal between said sleeve and said metal member and plug, the axial lengths of said sealing joints being relatively short compared to the diameters thereof.

4. A short, shallow seal for a lead-in construction for vacuum discharge apparatus, comprising a metal member adapted to form a part of the wall of a vacuum vessel, a metal electrode lead-in adapted to support an electrode, an insulating member fitting in said metal member for supporting directly said lead-in, said insulating member being formed of steatite, said lead-in passing through said insulating member, a metal plug secured to said lead-in and secured to said insulating member, the areas of contact between said insulating member and said metal member and plug having substantially cylindroidal form, whereby mechanical strains arising at the point of connection between the insulating member and the metal parts are taken up without provision of any other support for the electrode, said metal member and plug being formed of material having substantially the same coefficient of expansion as steatite, and sealing joints of a fused material at said areas of contact forming a vacuum tight seal between said insulating member and said metal member and plug, the axial lengths of said sealing joints being relatively short compared to the diameters thereof.

5. A short, shallow seal for a lead-in construction for vacuum discharge apparatus, comprising a metal member adapted to form a part of the wall of a vacuum vessel, a metal electrode lead-in adapted to support an electrode, an insulating member fitting in said metal member for supporting directly said lead-in, said insulating member being formed of steatite, said lead-in passing through said insulating member, a metal plug secured to said lead-in and secured to said insulating member, the areas of contact between said insulating member and said metal member and plug having substantially cylindroidal form, whereby mechanical strains arising at the point of connection between the insulating member and the metal parts are taken up without provision of any other support for the electrode, said metal member and plug being formed of material hav-

ing substantially the same coefficient of expansion as steatite, and sealing joints of a fused material selected from the group consisting of glass and enamel and having substantially the same coefficient of expansion as steatite at said areas of contact forming a vacuum tight seal between said insulating member and said metal member and plug, the axial lengths of said sealing joints being relatively short compared to the diameters thereof.

6. A short, shallow seal for a lead-in construction for vacuum discharge apparatus, comprising a metal member adapted to form a part of the wall of a vacuum vessel, a metal electrode lead-in adapted to support an electrode, an insulating member fitting in said metal member for supporting directly said lead-in, said insulating member being formed of steatite, said lead-in passing through said insulating member, a metal plug secured to said lead-in and secured to said insulating member, the areas of contact between

said insulating member and said metal member and plug having substantially cylindroidal form, whereby mechanical strains arising at the point of connection between the insulating member and the metal parts are taken up without provision of any other support for the electrode, said metal member and plug being formed of material having substantially the same coefficient of expansion as steatite, and sealing joints formed by fusion of said steatite with said metal member and plug at said areas of contact forming a vacuum tight seal between said insulating member and said metal member and plug, the axial lengths of said sealing joints being relatively short compared to the diameters thereof.

7. In a device as claimed in claim 6, said metal member and plug being composed of an alloy selected from the group consisting of nickel-iron, chromium-iron, vanadium-iron, and chromium-nickel alloys.

WALTER DÄLLENBACH.
